UNITED STATES PATENT OFFICE.

VINTON E. SISSON, OF CHICAGO, ILLINOIS, ASSIGNOR TO WALTER P. MURPHY, OF CHICAGO, ILLINOIS.

CORRUGATED METAL END FOR RAILWAY CARS.

Application filed October 1, 1920. Serial No. 414,056.

To all whom it may concern:

Be it known that I, VINTON E. SISSON, a citizen of the United States, residing at Chicago, in the county of Cook and State of Illinois, have invented new and useful Improvements in Corrugated Metal Ends for Railway Cars, of which the following is a specification.

This invention relates to improvements in end structures for railway cars and more particularly to sheet metal ends for freight cars.

The end of a freight car is subject to very severe shocks and stresses on account of the tendency of the cargo to shift when the train starts and stops and in switching and also to the tendency of the superstructure of the car to weave while the train is in motion. To strengthen this type of car, ends have been constructed of one or more sheets or panels of metal, usually steel, which sheets or panels are formed with corrugations for rigidifying the structure to more readily meet impacts from without, cargo thrusts from within, and the racking strains from weaving.

It is the object of this invention to provide an end of the sheet metal type which is adaptable to either wooden car frames or all metal freight cars and that may be employed for strengthening gondola cars, box cars, or other similar cars. It is a further object of this invention to provide the sheets or panels of the end with corrugations of particular contour that from their form and length are peculiarly adapted to meet the stresses and strains already described. While the corrugations are preferably formed parallel, their relation to each other or their direction is immaterial.

While the preferred forms of this invention are illustrated upon the accompanying sheets of drawings, yet it is to be understood that minor detail changes may be made without departing from the scope thereof.

In the drawings:

Figure 1 is a view in end elevation of a box car illustrating an embodiment of this invention.

Figure 2 is a view in horizontal section through the end taken on the line 2—2 of Figure 1.

Figure 3 is a view in section taken on the line 3—3 of Figure 2.

Figure 4 is a view in section taken on the line 4—4 of Figure 2.

Figure 5 is a view in section taken on the line 5—5 of Figure 2.

Figure 6 is a view in section taken on the line 6—6 of Figure 2.

Figure 7 is a fragmentary view of the corner of a panel.

Figure 8 is a sectional view taken on the line 8—8 of Figure 7 with the parts beyond the line shown in perspective.

The embodiment of this invention is illustrated in the drawings as applied to a box car and shows the end comprising two or more sheets or panels 1, preferably of 70 pressed steel, which are attached to the corner posts, end plate and end sill in the usual manner. Figure 2 illustrates a means for attaching the panels to the wooden corner posts 2 by flanging the ends of the panels 75 and securing the flanges to the posts. A plurality of strengthening corrugations are formed in each panel which merge at their ends into the plane of the panel so that the panel has a flat marginal portion about its edges.

In the form illustrated in the first eight figures of the drawings the corrugations are pressed from opposite sides of the sheet or panel with each corrugation having a constant change in depth from the center until it merges into the plane of the panel. The contour of the corrugations at the center is shown in the enlarged sectional view of Figure 3 and the manner in which the corrugations vary and merge into the plane of the panel is shown in Figures 4, 5 and 6. At the center, the main walls 3 are flat, equally spaced and substantially perpendicular to the plane of the panel. The main walls are 95 connected at this point by flat portions 4, the vertical elements of which are substantially parallel to the plane of the panel, the portions as a whole sloping from the center to the ends of the corrugations, where they 100 merge into the margins of the sheet. The flat portions 4 are substantially equal in width to the width of the surface of the main walls. As the corrugations taper from the center toward their ends, the angular relations of the main walls make a constant change, obliquing away from their connecting portions while said portions decrease constantly in width with their longitudinal center lines remaining parallel and said por- 110

tions on opposite side of the center remaining in the same respective planes until both main walls and connecting portions merge into the plane of the panel.

- 5 5. A wooden lining 7 is provided on the inner side of the end with a plurality of filler blocks 8 received within and attached to a number of corrugations to which the lining is secured. These blocks are tapered 10 and beveled according to the form of corrugation in order that the wooden lining may be secured in a position parallel to the panel.

The corrugations form in effect beams 15 having compression and tension members with the greatest strength at the center, where it should be, to resist centrally concentrated or equally distributed loads, or impacts in this particular construction. The 20 amount of metal located at a distance from the neutral axis of the panel is constantly reduced from the center to the ends of the corrugations. The maximum stretching or drawing in of the plate in pressing is at the 25 center and is constantly and proportionately reduced from the center to the ends of the corrugations. The compression and tension members are positioned away from the neutral axis of the panel and are connected by 30 the main walls. The compression and tension members, the oppositely disposed flat connecting portions, vary in width from the center to the ends and the angular relation of the webs to the plane of the panel varies from the perpendicular at the center in accordance with the width of the compression and tension members until all merge into the panel.

What I claim is:

- 40 1. A metal panel for car ends having a plurality of corrugations therein formed with compression and tension members of increasing strength from ends to center.
- 45 2. A metal panel for car ends having a plurality of corrugations therein formed with compression and tension members of increasing strength from ends to center and webs connecting said members having a varying angular relation to said members.
- 50 3. A metal panel for car ends having a plurality of corrugations formed therein with main walls substantially equidistant apart and perpendicular to the plane of the panel adjacent the center, connected by 55 members constantly varying in width from ends to center.
4. A metal panel for car ends having a plurality of corrugations formed therein with main walls substantially equidistant apart and perpendicular to the plane of the panel adjacent the center, the angular relation of said main walls to the panel constantly varying from ends to the center.
- 60 5. A metal panel for car ends having a plurality of corrugations formed therein

with main walls substantially equidistant apart and perpendicular to the plane of the panel adjacent the center, the angular relation of said walls to the panel constantly varying from ends to center, said main walls connected by members constantly varying in width from ends to center. 70

6. A metallic panel for car ends having a plurality of corrugations formed therein with main walls substantially equidistant apart and perpendicular to the plane of the panel adjacent the center, said main walls varying in width from ends to center, said main walls connected by members varying 75 in width from ends to center. 80

7. A metallic panel for car ends having a plurality of corrugations formed therein with main walls substantially equidistant apart and perpendicular to the plane of the panel adjacent the center, said main walls connected by members varying in width from ends to center, said corrugations of uniform width measured on the neutral axis 85 of the corrugations. 90

8. A metallic panel for car ends having a plurality of corrugations formed therein with main walls substantially perpendicular to the plane of the panel adjacent the center, connected by members constantly varying 95 in width from ends to center. 95

9. A metallic panel for car ends having a plurality of corrugations formed therein with main walls substantially perpendicular to the plane of the panel adjacent the center, the angular relation of said main walls to 100 the panel constantly varying from ends to the center. 100

10. A metallic panel for car ends having a plurality of corrugations formed therein with main walls having a similar angular 105 relation to the plane of the panel adjacent the center, said angular relation of main walls constantly varying from center to end, said walls connected by compression and tension members. 110

11. A metallic panel for car ends having a plurality of corrugations formed therein with main walls substantially perpendicular to the plane of the panel adjacent the center, the angular position of said walls to the 115 panel constantly varying from ends to center, said main walls connected by members constantly varying in width from ends to center. 115

12. A metallic panel for car ends having a plurality of corrugations formed therein with main walls having a similar angular relation to the plane of the panel adjacent the center, said angular relation of main walls constantly varying from center to end, 125 said walls connected by members which vary in width from center to end. 120

13. A metallic panel for car ends having a plurality of corrugations formed therein with main walls substantially perpendicular 130

- to the plane of the panel adjacent the center, said main walls varying in width from ends to center, said main walls connected by members varying in width from ends to center.
14. A metallic panel for car ends having a plurality of corrugations formed therein with main walls having a similar angular relation to the plane of the panel adjacent the center, said angular relation and width of main walls constantly varying from center to ends, said walls connected by members which vary in width from center to end.
15. A metal panel for car ends having a plurality of corrugations therein formed with main walls substantially perpendicular to the plane of the panel at the center connected by members, the angular relation of the main walls constantly varying from ends to center.
16. A metal panel for car ends having a plurality of corrugations therein formed with main walls having a similar angular relation to the plane of the panel adjacent the center connected by members, the angular relation of the main walls constantly varying from ends to center.
17. A metal panel for car ends having a plurality of corrugations therein formed with main walls substantially perpendicular to the plane of the panel at the center connected by members having a width constantly varying from ends to center, and the angular relation of the main walls constantly varying from ends to center.
18. A metal panel for car ends having a plurality of corrugations therein formed with main walls having a similar angular relation to the plane of the panel adjacent the center connected by members having a width constantly varying from ends to center, and the angular relation of the main walls constantly varying from ends to center.
19. A metal panel for car ends having a plurality of corrugations therein formed with main walls substantially perpendicular to the plane of the panel at the center connected by members having a width constantly varying from ends to center, the width of the main walls constantly varying from ends to center.
20. A metal panel for car ends having a plurality of corrugations formed therein having their longitudinal centers substantially equidistant connected by members having a width constantly varying from ends to center, and the angular relation of the main walls constantly varying from ends to center.
21. A metal panel for car ends having a plurality of corrugations formed therein having their longitudinal centers substantially equidistant connected by members
- having a width constantly varying from ends to center, and the width of the main walls constantly varying from ends to center.
22. A metal panel for car ends having a plurality of corrugations formed therein having their longitudinal centers substantially equidistant connected by members having a width constantly varying from ends to center, and the width of the main walls constantly varying from ends to center relative to the variation in width of the connecting members.
23. A metallic panel for car ends having a plurality of corrugations formed therein having their longitudinal centers substantially equidistant apart and connected by members constantly varying in width from ends to center.
24. A metallic panel for car ends having a plurality of corrugations formed therein having their longitudinal centers substantially equidistant apart, and the angular relation of said main walls to the panel constantly varying from ends to the center.
25. A metallic panel for car ends having a plurality of corrugations formed therein having their longitudinal centers substantially perpendicular to the plane of the panel, said main walls connected by members varying in width from ends to center, said corrugations of uniform width measured on the neutral axis of the corrugations.
26. A metallic panel for car ends having a plurality of corrugations formed therein having their longitudinal centers substantially equidistant apart, said main walls connected by members varying in width from ends to center, said corrugations of uniform width measured on the neutral axis of the corrugations.
27. A metallic panel for car ends having a plurality of varying depth corrugations formed therein with the maximum depth adjacent their center, said corrugations comprising main walls having similar angular relation to the plane of the panel adjacent the center, said angular relation of main walls constantly varying from center to end, said main walls connected by compression and tension members.
28. A metallic panel for car ends having a plurality of varying depth corrugations formed therein with the maximum depth adjacent their center, said corrugations comprising main walls having similar angular relation to the plane of the panel adjacent the center, said angular relation of main walls constantly varying from center to end, said main walls connected by members which vary in width from center to end.
29. A metallic panel for car ends having a plurality of varying depth corrugations formed therein with the maximum depth adjacent their center, said corrugations com-

prising main walls having similar angular relation to the plane of the panel adjacent to the center, said angular relation and width of main walls constantly varying from center to end, said main walls connected by members which vary in width from center to end.

30. A metallic panel for car ends having a plurality of parallel corrugations of uniform width the major portion of their length and varying depth but varying in cross sectional contour.

VINTON E. SISSON.
